UNITED STATES PATENT OFFICE.

HENRY KURTZ, OF ELGIN, ILLINOIS, ASSIGNOR TO THE LEA COMPANY, OF ELGIN, ILLINOIS, A CORPORATION OF ILLINOIS.

HORSE COLLAR.

Application filed November 6, 1924. Serial No. 748,017.

This invention which relates to a collar for draft animals, is concerned with certain features of construction by which the appliance is rendered more easily adjustable 5 for use. It is also concerned with a pad forming part of the collar, and with the means by which the pad is operatively associated therewith. Accordingly it is toward objects and purposes such as these, as well 10 as others which will presently appear, that my invention is primarily directed.

An embodiment of this invention in a preferred form is shown in the accompanying drawings wherein—

15 Figure 1 is a fragmentary view in elevation of the upper portion of the collar;

Fig. 2 is a top plan view thereof;

Fig. 3 is a similar view of the neck pad per se; and

20 Figs. 4 and 5 are transverse and longitudinal sections therethrough, on lines 4—4 of Fig. 3, and 5—5 of Fig. 4, respectively.

The collar A, as shown, is provided with upper end portions which terminate in overlapping flaps 6 and 7. To one of these flaps, remote from its end, is secured a pair of buckles 8 for adjustable connection with two billets 9 whose ends are joined to a common loop member 10. A cam lever 11 is carried 30 by the other flap for operative connection with the loop member, whereby the two billets may be easily and forcibly drawn taut after being adjusted within the buckles. In this manner I provide for adjusting the 35 collar accurately upon the neck of the animal.

Associated with a collar so formed is a pad B of special construction. It consists 40 preferably of a form plate 12 of bendable sheet metal suitably arched to fit over the back of the neck. Underlying this form is a cushion layer 13, preferably of heavy felt. I also provide for the pad a two-piece covering of leather, one piece 14 underlying the 45 cushion layer and extending past the front and rear edges of the form plate to execute an upward bend, and the other covering piece 15 connecting as at 16 with the first and shaped to repose upon the form plate, 50 as shown. The two covering pieces together along their joined edges provide a pair of flanges 17 extending upwardly and outwardly in a manner which adapts the pad to fit properly within the collar beneath the 55 overlapped flaps thereof.

Both covering pieces of the pad are shown to be extended transversely for an appreciable distance beyond the ends of the form plate, the lower piece 14 being preferably longer than the other. To the unsupported 60 ends of the pad covering I fasten two straps 18 and co-operating buckles 19 by which the pad may be loosely secured within the collar in any of the various adjusted positions of its billets.

65 The collar which I have described herein with some particularity is advantageous in many respects. It is quickly adjustable to necks of horses which may vary widely in size; its range or extent of adjustability is 70 sufficiently great to adapt a single sized collar for use with most draft animals; the pad itself is very easy to produce, and also to bend in conformity with the animal's neck whereon it is rested; and finally the 75 pad is comfortable when worn on account of its form plate affording the animal protection from the metallic fastening devices on the flaps, their reinforcing studs, rivets, etc. In this same connection, it will be noted 80 that in my improved collar, none of these fastening parts are directly over the neck, but are situated slightly upon the sides thereof, this being desirable for the reasons mentioned. With such a collar the present 85 pad may, of course, co-operate successfully, although where the metallic fastenings are directly over the neck, its use would have an even greater advantage.

I claim:

A pad for use with an adjustable horse collar comprising a pair of leather pieces in layer formation united adjacent their front and rear edges which are upturned to provide flanges between which the collar may 90 be received, a stiffening plate of bendable metal interposed between the leather pieces, the plate being arched longitudinally but flat in a transverse direction and terminating short of all the edges of the enclosing 95 leather pieces, a cushioning layer of felt arranged between the plate and the under leather piece, and means secured to the upper leather piece at a point beyond the plate 100 to connect the pad loosely with the collar, 105 substantially as described.

HENRY KURTZ.
